United States Patent Office

Des. 206,828

Patented Jan. 31, 1967

206,828

JUG

Alan J. Fox, Sewickley, Pa., assignor to Sinclair-Koppers
Company, a partnership of Delaware

Filed Feb. 28, 1966, Ser. No. 1,198

Term of patent 14 years

(Cl. D58—5)

FIG. 1

FIG. 2 is a side elevational view with the jug turned clockwise 45 degrees from the position seen in FIG. 1; and

FIG. 3 is a top plan view thereof.

I claim:

The ornamental design for a jug, as shown and described,
